UNITED STATES PATENT OFFICE

VICTOR L. BELL, OF EDGEWOOD, PENNSYLVANIA

DRAFTING COMPASS

Application filed May 9, 1928. Serial No. 276,245.

My invention relates to drawing instruments and particularly to bow pencils or pens for scribing small circles, wherein the instruments are provided with pointed pencils or 5 pen stili.

In the usual bow pencil construction, the pencil point is so adjusted with respect to the pivot point that the points are in a plane normal to the plane of the handle. A circle 10 may then be scribed on the surface of the drawing paper with but slight penetration of the pivot point into the paper.

As the pencil or pen point wears, in order to bring the point into contact with the paper 15 while the handle of the instrument is perpendicular to the surface of the paper, it is necessary to press the pivot point deeper into the drawing paper each succeeding operation with the result that the point makes permanent unsightly pin holes.

An object of my invention is to provide a drawing instrument or bow pencil or pen 20 wherein the pivot point is yieldingly mounted so that, as the point wears, it may be brought into working contact with the paper or surface by slight pressure applied at the handle which compresses a spring supporting the pivot point and prevents undue penetration of the point. Tilting of the instrument 25 to bring the stylus into contact with the surface is rendered unnecessary and slipping of the point from its socket in the surface is eliminated.

A further object of my invention is to provide a drawing instrument having the above- 30 noted characteristics wherein the pivot point is mounted on one arm of the instrument for longitudinal movement and wherein a spring within a receptacle for the pivot point serves 35 to yieldingly bias the point to its outermost position.

A further object of my invention is to provide a drawing instrument or bow pencil or pen 40 wherein the tension of the movable pivot point may be adjusted to obtain the required tension on the pivot point to prevent undue penetration of the point regardless of wear of the working stylus.

A further object of my invention is to provide a drawing instrument having the above- 45

noted characteristics that is simple in construction and inexpensive to manufacture.

These and other objects that will be made apparent throughout the further description of my invention are attained in the instrument to be hereinafter described and illustrated in the accompanying drawings, 55 wherein:

Figure 1 is a view partially in side elevation and partially in section, of a drawing 60 instrument embodying features of my invention;

Fig. 2 is an elevational view of the device shown in Fig. 1, turned ninety degrees;

Fig. 3 is a longitudinal sectional view in 65 enlarged scale of a fragment of the instrument shown in Fig. 1; and

Fig. 4 is a longitudinal sectional view of a fragment of a modified form of instrument.

Referring to the drawings wherein a bow 70 pencil is illustrated for the purpose of example, the instrument comprises the usual bow pencil construction with the exception of the mounting for the pivot point and consists of a pair of integral resilient arms 5 and 6 having flexible portions 7 and 8, respectively, jointed at 9 and provided with a knurled handle 11 that is adapted to be gripped between the thumb and fingers of the operator. 75

The arms are normally biased by the flexible portions to extreme separated angular positions and are adjusted by means of a screw 12 pivoted to the arm 5 and extending through an opening 13 in the arm 6. A thumb screw 14 upon the screw 12 may be 80 adjusted to bring the arm 13 into the desired relation.

The arm 6 is provided at its free end with a split socket or clamp 15 for receiving a pointed pencil stylus 16, the clamp being controlled by a thumb screw 17. The arm 5 is provided with a detachable extension 18 having a pin 19 which snugly fits into a recess 21 in the arm 6. The extension 18 is also provided with a recess 22 that is closed 85 by a threaded plug 23 in which a pivot point 24 is slidably mounted. An enlarged head 25 on the point 24 limits outward movement thereof and a spring 26 yieldingly biases the point to its outermost position, as shown in 90 100

Fig. 4. The point 24 is provided with the usual paper penetration tip or point 27 and the pencil point or stylus is usually so adjusted that the points are in a plane normal to that of the handle 11, as shown in Fig. 1.

As the point of the stylus 16 wears away, slight pressure on the handle 11 compresses the spring until the stylus again engages the surface being marked. Readjustment of the stylus at frequent intervals is not necessary, as is the case with present instruments and, accordingly, considerable time is saved. All circles can be uniformly made and the absence of unsightly pin-holes results in a drawing of neat appearance. Tilting of the instrument to bring the stylus into contact with the surface being marked is unnecessary, and the danger of causing the pivot point to slip from its socket is eliminated.

In Fig. 4 I have shown a modified form of point mounting wherein the tension of the spring 26 is rendered adjustable, the mounting being provided with a screw plug 23 that is provided with a slot 28 for receiving a spanner wrench, by means of which the plug may be removed. To increase the tension of the spring 26, discs 29 are added until the desired tension is obtained. It is obvious that other means may be employed to obtain spring adjustment.

While I have shown, for the purpose of illustration, a bow pencil, it will be understood that the invention is equally applicable to bow-pens, since the pivot point may be depressed sufficiently to bring both nibs of the bow pen in contact with the surface being marked and since wearing of the nibs makes longitudinal adjustment of the pivot point necessary. It will be understood that the term stylus appearing in the claims applies to pencil and pen points.

While I have illustrated and described but two embodiments of my invention, it will be apparent to those skilled in the art that various changes, modifications, substitutions, additions and omissions may be made therein without departing from the spirit and scope of my invention, as set forth in the appended claims.

I claim as my invention:

1. A drawing instrument comprising a pair of pivotally connected arms, a clamp on one arm for retaining a marking stylus, the free end of the other arm having a receptacle for a pivot point, a perforate plug for the receptacle, a pivot point slidably mounted in the plug, and a spring within the receptacle engaging the inner end of the point for yieldingly urging it to its outermost position.

2. A drawing instrument comprising a pair of pivotally connected arms, one of which is provided with a non-yielding stylus which becomes shortened with use and the other with a longitudinally movable centering point about which the stylus is rotated

and means whereby said point is yieldingly biased toward an extreme outward position.

3. The combination with a drawing instrument for marking circles on a surface and having a pivot arm and a stylus arm pivotally connected, the latter being provided with a non-yielding stylus and disposed relatively close to the pivot arm and adapted to be revolved about the pivot arm in marking a circle, of yielding means whereby said pivot arm may be temporarily shortened by the application of pressure in a direction substantially perpendicular to and toward the surface, for bringing the stylus into contact with the surface while the pivot arm is held substantially perpendicular to the surface.

In testimony whereof, I have hereunto subscribed my name this 5th day of May, 1928.
